(57) **CLAIM**

The ornamental design for a rear fork for allterrain vehicle, as shown and described.

DESCRIPTION

1. Rear fork for allterrain vehicle

1.1 is a top, rear and left-side perspective view of a rear fork for allterrain vehicle embodying my new design;

1.2 is a left-side elevation view thereof;

1.3 is a right-side elevation view thereof;

1.4 is a front elevation view thereof;

1.5 is a rear elevation view thereof;

1.6 is a top plan view thereof;

1.7 is a bottom plan view thereof;

1.8 is a bottom, rear and right-side perspective view thereof;

1.9 is a top, rear and right-side perspective view thereof; and

1.10 is a top, rear and left-side perspective view thereof, the view being tilted slightly lower than 1.1.

The product incorporating the design is used as a rear fork for allterrain vehicle; The essential features of the design lie in its shape; The rear perspective view in figure 1.1 is designated to best show the essential feature of the design.

1 Claim, 10 Drawing Sheets
